UNITED STATES PATENT OFFICE.

WILLIAM J. NEWTON, OF LYNBROOK, AND MORRIS GOLDBERG, OF BROOKLYN, NEW YORK, ASSIGNEES TO NEWTON MANUFACTURING COMPANY, OF LYNBROOK, NEW YORK, A CORPORATION OF NEW YORK.

ELECTRIC WALL-SWITCH.

1,248,384.

Specification of Letters Patent. Patented Nov. 27, 1917.

Application filed July 13, 1916. Serial No. 108,999.

To all whom it may concern:

Be it known that we, WILLIAM J. NEWTON, of Lynbrook, in the county of Nassau and State of New York, and MORRIS GOLDBERG, of the borough of Brooklyn, city and State of New York, have invented certain new and useful Improvements in Electric Wall-Switches, of which the following is a description.

10 Our invention relates to wall switches, and particularly to means for securing the customary face-plate to the switch supporting means.

15 Wall switches now in common use are provided with two push-buttons for opening and closing the switch, which push-buttons project through the face-plate. The face-plate is secured to the bridge-plate or switch supporting means by means of screws usually placed directly in line with the push-buttons. Such a construction is incapable of even the slightest adjustment between the switch-supporting means and the face-plate, and, on account of the presence of the screws, 20 is extremely unsightly. It is furthermore difficult to fix it securely in place, since the attaching screws must necessarily be very small, and the thickness of the bridge-plate is so slight that the threads formed therein 25 for the screws are necessarily very weak.

An object of our invention is to provide a face-plate supporting means which is adjustable relative to the button, toggle lever, or other switch-operating means, and which 30 therefore permits the plate to be properly set in a vertical or horizontal position, irrespective of the position of the switch itself.

A further object of our invention is to 35 provide attaching means whereby the face-plate will be securely attached to the bridge-plate or bridge-supporting means by means of parts of substantial strength so that they may be set up with considerable force.

40 A further object of our invention is to dispense with the unsightliness of the attaching screws and to substitute therefor attaching means which are ornamental in appearance.

45 Our invention may be applied to any of 50 the ordinary types of wall switches, but find its greatest usefulness in connection with the toggle switch described in the Newton Patent No. 1,233,597, and the single push-button switch shown in the Newton Patent

No. 1,186,930, since with these types of switch 55 the greatest adjustment can be secured and the size of the plate may be reduced to a minimum.

Referring to the drawings, Figure 1 is a front view of our improved switch-plate attaching means applied to the toggle switch shown in the Newton Patent No. 1,233,597.

Fig. 2 is a side elevation thereof, partly in section;

Fig. 3 is a fragmentary view thereof on an 65 enlarged scale showing the means for securing the face-plate in condition, the concealing shield being removed;

Fig. 4 is a longitudinal sectional view thereof, showing means for securing the 70 face-plate in position, including the concealing shield;

Fig. 5 is a perspective view of a wrench which may be employed in assembling our 75 improved device;

Fig. 6 is a fragmentary front view of our improved switch attaching means as applied to the ordinary type of double push-button switch;

Fig. 7 is a sectional view thereof; 80

Fig. 8 is a fragmentary sectional view of a modification of our improved switch-plate attaching means applied to the single push-button switch of the Newton Patent No. 1,186,930. 85

In all of the modifications, the switch-supporting means or bridge-plate 10 has preferably mounted thereon a screw-threaded collar, such as shown at 11 in Fig. 4. It will be understood that in the case of the 90 two button switch, two collars, one for each button, are provided. The switch-operating means in each case passes through the collar 11, such switch-operating means being the toggle lever 12 shown in Figs. 1, 2, 3 and 4, 95 or the push-buttons 12^a, shown in Figs. 6, 7 and 8. Any other type of switch-operating means may, however, be substituted for the levers 12 and 12^a.

In the modification shown in Figs. 1, 2, 3, 100 4, 6 and 7, the face-plate 13 is provided with an aperture 14 for each collar 11, and is adapted to fit loosely over the collar after the switch supporting means 10 have been secured to the wall. To firmly retain the 105 face-plate 13 in position, we employ a screw-threaded member 15 adapted to coöperate with the screw-threaded collar 11, as shown

in Fig. 4. This member 15 is preferably provided with a nut-head 16, such as is shown in Fig. 3, to permit the application of a wrench or similar device thereto. This 5 construction enables the operator to screw the member 15 tightly against the face-plate 13. We preferably provide a wrench such as is shown in Fig. 5 for this purpose. After the face-plate 13 has been firmly 10 secured in the desired position by means of the member 15, a shield provided with an annular recess of sufficient size to cover the nut-head 16, such as indicated at 17, is preferably screwed upon the screw-threaded collar 11, as is shown in Fig. 4, to conceal the 15 collar and the member 15, and thus add to the appearance of the switch. This shield is provided with an aperture 18, through which the lever 12 or other switch-operating 20 device projects.

The manner of operation of our invention should be clear from the above. The switch-supporting means 10 having been secured to the wall, the face-plate 13 is placed in position 25 with its aperture 14 fitting loosely over the collar 11. It is not essential, in the modifications shown in Figs. 1, 2, 3, 4 and 8, that the switch-supporting means 10 be inserted in the wall in an exactly straight position, as is necessary with the switches now 30 generally in use, since the face-plate 13 can be moved angularly, as desired, with respect to the switch-supporting means. For this purpose the face-plate is countersunk, as 35 shown at 19, to receive the lugs 20. After the face-plate has been adjusted so that it assumes the desired position with respect to the wall, irrespective of any inclination of the switch-supporting means. For this 40 purpose the face-plate is screwed tightly against the face-plate and thus holds the face-plate firmly in position. The wrench shown in Fig. 5, which is preferably used for this purpose, is so constructed that its greatest diameter is 45 not in excess of the diameter of the shield 17, so that any scratching of the plate, due to the use of the wrench, will be concealed by said shield. After the face-plate 13 and the member 15 have been applied as above 50 described, the shield 17 is screwed upon the collar 11 to effectively conceal the unsightly collar 11 and member 15.

In the modification shown in Fig. 8, we dispense with the nut 15 and use the shield 55 17 as the attaching member. In this case, the aperture in the face-plate fits snugly over the collar 11, and is held in place by screwing down the shield 17 as tightly as possible. For this purpose the shield 17 may be knurled so as to permit easy manipulation with the fingers.

It will be understood that in the modification shown in Figs. 1 to 4, and 6 and 7, the nut 15 may be flat, *i. e.*, the portion which enters the face-plate 13 may be dispensed

with, or the portion which enters the face-plate 13 may be tapered so as to make a closer contact between the aperture of the face-plate and the nut.

We therefore do not wish to limit ourselves to the particular forms shown and described, since many changes may be made therein without departing from the spirit of our invention. 70

What we claim is:

1. In a device of the character described, the combination of switch-supporting means, a screw threaded collar thereon, a face-plate provided with an opening adapted to encircle said collar, a screw-threaded member 80 extending between the collar and the face-plate and provided with a nut-head and adapted to coöperate with said collar to retain the face-plate in position, and a screw-threaded shield adapted also to coöperate 85 with said collar to conceal said screw-threaded member and said collar.

2. In a device of the character described, the combination of switch-supporting means, a screw-threaded collar thereon, a switch-operating device projecting through said 90 collar, a face-plate provided with an opening adapted to loosely encircle said collar and said device, a screw-threaded member 95 extending between the collar and the face-plate and provided with a nut-head outside the face-plate and adapted to coöperate with said collar to retain the face-plate in position, and a screw-threaded shield adapted to 100 coöperate with said collar to conceal said screw-threaded member and said collar.

3. In a device of the character described, the combination of switch-supporting means, a screw-threaded collar thereon, switch-operating means projecting through 105 said collar, a face-plate provided with an opening adapted to loosely encircle said collar and said device, a screw-threaded member provided with a nut-head and adapted to coöperate with said collar to retain the face-plate in position, and a screw-threaded shield adapted to 110 coöperate with said collar to conceal said screw-threaded member and said collar.

4. In a device of the character described, 115 a bridge, a screw threaded collar mounted thereon, a face-plate having an aperture of larger diameter than the collar, a screw-threaded nut adapted to engage the collar and project between the collar and the face-plate and a screw-threaded shield adapted to 120 engage the collar and cover the nut and collar.

5. In a device of the character described, 125 a switch supporting bridge, a screw-threaded collar mounted thereon, switch operating means projecting through the collar, a face-plate having an aperture larger than the collar, a screw-threaded nut adapted to engage the collar and having an annular 130

projection the outer diameter of which is substantially the diameter of the aperture in the face-plate and a screw-threaded shield having a recess and adapted to engage the 5 collar and conceal the collar and nut.

6. In an apparatus as described, a switch supporting means, a collar attached thereto, an apertured face plate adapted to loosely encircle said collar, a nut having a shank

which coöperates with said collar and fits 10 snugly in the aperture of said face plate and a head that firmly contacts with said face plate, and an apertured shield adapted to cover said nut and said collar and to be firmly held against said face plate.

WILLIAM J. NEWTON.
MORRIS GOLDBERG.
